UNITED STATES PATENT OFFICE.

MERRILL M. WILCOX, OF SAGINAW, MICHIGAN.

METHOD FOR THE RAPID PRODUCTION OF SETS OF CASTINGS.

Application filed May 31, 1924. Serial No. 716,977.

To all whom it may concern:

Be it known that I, MERRILL M. WILCOX, a citizen of the United States, residing at Saginaw, in the county of Saginaw and 5 State of Michigan, have invented certain new and useful Improvements in Methods for the Rapid Production of Sets of Castings; and I do hereby declare the following to be a full, clear, and exact description of 10 the invention, such as will enable others skilled in the art to which it appertains to make and use the same.

This invention relates to an improved method of producing castings, such as piston 15 rings and other small pieces that are to be fabricated for use in the assembly of machines, as motors for aeroplanes, automobiles and the like.

The objects of my improved method are to 20 simplify and expedite production in order to more rapidly and cheaply produce multiple sets of castings. For example my improved method as applied to the production of engine parts, say, cast piston rings, enables me to also produce, without any additional molding labor, sets of other parts for 25 the same engine assembly, and to make both sets of castings at a very fast rate of production and with a minimum of expense.

30 In carrying out my method I employ the "one-piece flask" method of machine-molding and adapt to that method an arrangement of patterns that has heretofore been employed only in two-piece flask molding.

35 By that adaptation I am enabled to accomplish a great saving and produce two assembly parts with the same labor heretofore required to produce one part.

By the term "one-piece flask" I designate 40 any flask member, either a cope or a drag, which in usual foundry practice is placed on the platen of a molding machine, filled with sand, rammed and struck off smooth on its top face, then lifted from the platen, bearing in its bottom face the imprints of 45 the group of patterns that are fixed to the platen.

The one-piece flask is then inverted and placed, mold face up, on a suitable board or 50 slab. Other like molded flasks are stacked upon the first until a series or nest of one-piece flasks is formed, the struck-off face of one mold forming the cover for the mold in the next flask below. A "tree" of castings 55 consisting of as many sets or groups as there are flask members in the stack can thus be

made at one pouring through a common gate.

My method is illustrated in the accompanying drawings, in which Fig. 1 is a perspective view of the patterns and the platen of a molding machine, with a cope thereon partly packed with molding sand, a wall of the cope broken away.

Fig. 2 is a perspective view of the rammed 65 cope resting on a base ready to receive other copes to be stacked thereon.

Fig. 3 is a vertical sectional view of a plurality of copes stacked to form a tree mold.

Fig. 4 is a side view of a pair of piston 70 ring castings with a spring washer and washer-retainer casting therein, the sprues indicated by dotted lines.

Fig. 5 is a perspective of a spring washer casting.

Fig. 6 illustrates a spring washer retaining casting in its three stages of manufacture, plain, bored, and split.

As previously indicated, it has been common in two-piece flask practice, that is, 80 where both a cope and drag are employed, to enclose a mold for a smaller piece of metal within the mold for a larger piece. This is done both to balance the pressure of the molten metal and to heat the sand core 85 from within and thereby prevent too rapid chilling of the enclosing or outer casting. The smaller piece of metal is usually scrapped, or used for some other purpose, such as abrasive chunks for foundry rattlers, 90 but not, so far as I am aware, for the production of other parts of the same machine assembly.

With certain modifications I utilize this two-piece flask system, but adapt it to the so-called one-piece flask system, that is, to a plurality of one-piece molds nested so as to produce a tree casting. As an essential feature of my improved method I place within any surrounding casting such as a piston 100 ring blank, another smaller casting which is one of the pieces required in the assembly of the completed machine. I thus accomplish a double purpose, viz, I not only warm the sand within the surrounding casting 105 while the mold is being poured as heretofore in two-piece flask molding; but I also produce, without any additional expense except the value of the actual metal used, another part of the machine, which part here- 110 fore has been made by striking up or stamping it from sheet metal.

By this means I produce quantities of parts such as piston rings, and as a by-product, at the same operation and without any additional labor cost I make proportionate quantities of other smaller engine parts which heretofore have required expensive machinery and high labor cost.

Referring now to the drawings, 1 represents the platen of a molding machine, on 10 which patterns 2, 2 are secured, and 3, 3 are smaller patterns arranged within the patterns 2, 2. 4 is a cope, drag or one-piece flask-member and 5 is the vertical core for the gate, connected by a horizontal channel 15 core 6 to the patterns 2, 2 and 3, 3 respectively.

In Fig. 2, 7 indicates the cavities or molds left in the sand when the flask-member 4 is lifted from the patterns on platen 1.

20 The vertical gate 8, indicated by dotted lines in Fig. 4, is formed by the metal poured into the nested flasks shown in Fig. 3.

25 The outer or surrounding castings, as piston rings 9, preferably enclose spring washer-castings such as shown in Fig. 5, these washers being adapted for use on the valve springs of the same engines in which the piston rings 2 are to be used. I may also 30 make in the same manner, retainers 11 for the spring washers 10. A washer retainer is shown in Fig. 6 as a conical plug to be later bored as at 12 and split as 13 to form the two-part conical bushing through which 35 the engine valve stem is passed.

These retainers 13 and the washers 10 have both heretofore been produced by separate operations from stamped metal, but in my improved method I obtain them in the 40 desired quantities along with piston rings, as above described, without any additional labor and no extra cost excepting that of the actual molten iron.

By employing this system for making

small parts of a given machine, namely, 45 molding them within other surrounding parts, and adapting that method to a system of one-piece molds that can be nested as described I rapidly and accurately produce "tree-castings" made up of quantities of 50 parts such as piston rings, and simultaneously produce corresponding quantities of other parts for the same machine as by-products, and it is in this adaptation that 55 my invention has its great value as a method for the rapid and cheap production of sets of engine parts.

Having thus described my invention, what I claim and desire to secure by Letters Patent is:

60 1. The herein described method for the economical and rapid production of machine-part castings which consists in forming in a face of a one-piece flask a plurality of connected molds, some of said molds formed from patterns for certain parts of said machine and enclosing other molds formed from smaller patterns of other parts of the same machine, assembling a 65 plurality of said one-piece flasks in inverted position to form a stack, and filling said molds with metal.

70 2. The herein-described method for the economical and rapid production of castings in multiple groups from different patterns molded in one-piece flasks, which consists in forming in a face of a one-piece flask a plurality of connected molds, some of said molds formed from certain patterns and enclosing other molds formed from smaller 75 patterns, assembling a plurality of said one-piece flasks in inverted position to form a stack, said one-piece flasks connected in series by a common gate, and filling said 80 molds with metal.

85 In testimony whereof I affix my signature.

MERRILL M. WILCOX.
